(57) **CLAIM**

The ornamental design for an epilator, as shown and described.

DESCRIPTION

FIG. 1 is a perspective view of an epilator showing my design;

FIG. 2 is another perspective view;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion of FIG. 3.

The broken lines illustrate the boundary of the enlarged portion and form no part of the claimed design.
